(57) **CLAIM**

The ornamental design for a screen door opening foot handle, as shown and described.

DESCRIPTION

FIG. 1 is a front perspective view of a screen door opening foot handle;

FIG. 2 is a rear perspective view thereof;

FIG. 3 is a front elevational view thereof;

FIG. 4 is a right side elevational view thereof;

FIG. 5 is a top plan view thereof;

FIG. 6 is a rear elevational view thereof;

FIG. 7 is a left side elevational view thereof; and,

FIG. 8 is a bottom plan view thereof.

The broken lines shown represent unclaimed subject matter
and form no part of the claimed design.

1 Claim, 3 Drawing Sheets
